UNITED STATES PATENT OFFICE

2,580,146

SEAM RIPPING ATTACHMENT FOR SEWING MACHINES

Lydia K. Williams, White Lake, S. Dak.

Application July 8, 1949, Serial No. 103,721

3 Claims. (Cl. 164—17.5)

1

This invention relates to a cutting attachment adapted to be mounted in the needle bar of a sewing machine and which will be operated by the sewing machine, when driven in a conventional manner, for quickly and efficiently cutting the threads of a seam to thereby rip out or open the seam without injury to the fabric and much more rapidly than it would otherwise be possible to accomplish such operation.

Still another object of the invention is to provide a seam ripping attachment for sewing machines wherein the ripping implement may also be utilized as a carrier for a very fine ripping needle or blade which may be detachably supported thereby for ripping out very fine seams and for cutting the fine threads thereof and which could not be cut with the primary ripping implement.

Still a further object of the invention is to provide a novel means for demountably supporting the fine ripping implement or needle in the primary ripping implement and so that the fine needle will be supported throughout a substantial portion of its length to minimize the danger of breakage thereof.

Various other objects and advantages of the invention will hereinafter become more fully apparent from the following description of the drawing, illustrating a presently preferred embodiment thereof, and wherein:

Figure 1 is a view showing the ripping implement assembled with the fine ripping needle and mounted in the needle bar of a sewing machine;

Figure 2 is an enlarged front elevational view of the assembled ripping implement including the fine ripping needle thereof;

Figure 3 is a view taken at right angles to Figure 2 and partly in section;

Figure 4 is a fragmentary front elevational view of the lower portion of the primary ripping element, with the fine ripping needle removed therefrom, and

Figure 5 is a cross sectional view of the assembled ripping device taken substantially along a plane as indicated by the line 5—5 of Figure 3.

Referring more specifically to the drawing, the ripping attachment for sewing machines in its entirety is designated generally 6 and includes a primary ripping element, designated generally 7 comprising an elongated body having an enlarged end or head 8, preferably of circular cross section and which is sized to detachably fit in a conventional needle bar 9 of a sewing machine, a portion of which is shown at 10 and which is secured therein in a conventional man-

2

ner as by means of the set-screw 11. The primary ripping implement 7 is provided with an elongated shank portion 12, which is likewise preferably of circular cross section but of smaller diameter than the head 8 and which is connected to said head in end-to-end relationship therewith by an integral frusto-conical portion 13. The shank portion 12 is provided with a groove 14 which extends substantially from end-to-end thereof and which is preferably provided with substantially parallel side walls which are disposed substantially perpendicular to the bed of the groove, as best illustrated in Figures 4 and 5. The shank 12, at its opposite outer end, 15 is beveled on four sides thereof as seen at 16 to provide cutting edges 16 at the outer end of said shank 12. One end of the groove 14 opens into one of the beveled surfaces 15 at its outer end, as best seen in Figure 4.

From the foregoing it will be readily apparent that the member 7 may be mounted as previously described in the needle bar 9 and may be reciprocated by the normal operation of the sewing machine 10 so that the edges 16 thereof will effectively function for cutting the threads of a seam in material which is fed in a conventional manner by the machine beneath its presser foot 17. Said edges 16 will function efficiently for cutting the threads of ordinary seams but is too large for cutting the threads in a very fine seam. However, the threads of a very fine seam may be cut by a relatively fine thread cutting needle, designated generally 18 which is substantially smaller in cross section than the shank portion 12. However, the needle 18 would ordinarily be of insufficient strength if mounted directly in the needle bar 9 and therefore to reinforce and support said needle 18 the groove 14 is provided in the shank 12 of the thread cutting member 7 to receive a substantial portion of the needle 18 which fits relatively snug therein, as clearly illustrated in Figures 2 and 3. The cutting needle 18 is longer than the groove 14 so that its lower end extends beyond the lower, open end of the groove 14 and to beyond the cutting edges 16 and has its terminal beveled, as seen at 19 to provide cutting edges 20. The opposite, upper end of the needle 18 abuts against the upper, closed end 21 of the groove 14 and said cutting needle 18, adjacent its upper end, is thickened to provide a wedge shape portion 22 which protrudes slightly from the groove 14, whereas the remainder of the portion of the needle 18 which engages the groove 14 does not project outwardly therefrom.

A retaining collar 23 is slidably and detachably mounted on the shank 12 and is applied thereto over the lower end of the needle 18 and the lower end of said shank 12 and is moved upwardly on the shank 12 until the bore of said collar 23 is positioned in wedging engagement with the wedge portion 22 for thereby detachably securing the cutting needle 18 in the groove 14.

Accordingly, it will be readily apparent that when the head 8 is secured in the needle bar 9 and the fine cutting needle 18 is secured, as previously described, in the groove 14 of the shank 12, the finer cutting edge 26 of the needle 18 may be utilized for ripping finer seams of finer material, such as silk, when the sewing machine 10 is operated in a conventional manner, as previously described. The coarser thread cutting or seam ripping member 7 is preferably employed for ripping seams of wool and cotton.

The head 8 is made of sufficient length so that it may be extended further into the needle bar 9 when the fine cutting needle is used than when the ripping needle 7 is used alone.

Various modifications and changes are contemplated and may obviously be resorted to, without departing from the spirit or scope of the invention as hereinafter defined by the appended claims.

I claim as my invention:

1. A seam ripping implement for sewing machines comprising an elongated body member having an enlarged head at one end thereof adapted to be detachably secured in a needle bar of a sewing machine, an elongated shank forming a restricted extension of one end of the head and adapted to extend downwardly therefrom with respect to the needle bar, the lower, free end of said shank being beveled on four sides to provide a V-shaped cutting edge consisting of downwardly converging edge portions merging to form a point, said point being dis-

posed at the terminal of the lower end of the shank and in alignment with the axis thereof, and said shank having a longitudinal ripping needle receiving groove extending throughout a major portion of the length of the shank, said groove having a closed upper end and a lower end opening into certain of said beveled surfaces above the V-shaped cutting edge.

2. A seam ripping implement as in claim 1, said groove having a flat bed merging at the lower end of the groove into certain of the beveled surfaces and which is disposed above and spaced substantially equal distances from the converging edge portions of said cutting edge.

3. A seam ripping implement as in claim 1, said groove having a flat bed merging at the lower end of the groove into certain of the beveled surfaces and which is disposed above and spaced substantially equal distances from the converging edge portions of said cutting edge, said shank being of circular cross section above said beveled surfaces, and the depth of the groove being less than the length of a radius of the shank.

LYDIA K. WILLIAMS.
